ABSTRACT: A rectangular carton for storing packages of polymer, which carton is divided by intersecting partitions into four rectangular cells with each cell sized to hold snugly a single stack of such packages. The carton prevents bursting of the packages due to cold flow of the polymer during storage and shipping.

STORAGE CONTAINER

THE INVENTION

Synthetic elastomers such as butadiene/styrene polymers (SBR) and ethylene/propylene/diene polymers (EPDM) are normally stored and shipped in plastic or paper wrappings or bags containing about 34 kg. of polymer each. These packages, when freshly filled, normally have dimensions of about 18×35×70 cm. in the case of SBR and 18×41×61 cm. for EPDM but upon storage and/or shipping the polymer tends to settle or cold-flow to such an extent that even under normal conditions of storage and handling the packages are frequently subjected to pressures exceeding their strength, resulting in bursting of the packages with resultant loss or contamination of polymer and the expense of recovery or replacement thereof. This difficulty is increased when the packages are stacked one upon the other on pallets and the pallets are tiered with other pallets. With certain polymers a single stack of five packages can produce exceedingly high pressures on the bottom container and bursting is commonplace even under normal storage and shipping conditions.

One solution to this problem has been to place such stacks of polymer-filled packages into close-fitting heavy wood boxes to restrain expansion of the packages during handling and shipping. This is practically prohibitively expensive due to the high cost of wood boxes as well as the labor cost in assembling them and the relatively heavy weight in handling and shipping. There has been a need for a cheap, easily assembled disposable, collapsible carton which would solve the shipping and storage problems associated with cold flow of elastomeric polymers.

In accordance with this invention there is provided a container for storing and shipping packaged materials which are subject to settling, expansion, or cold flow. This container is a rectangular box or carton of cardboard, corrugated paperboard or other suitable, flexible, cheap sheet material, divided by vertical partitions into at least four cells or compartments similar in cross section to and equal in height to the box. The term "rectangular" as applied herein to a three-dimensional structure such as a box, container or cell, refers to a right parallel piped, that is, a six-sided container with planar faces of which each face is in the form of a rectangle. This box is cheap enough to be discarded after use and is easily made from corrugated paperboard by first folding four sheets of paperboard to form four individual tubes or open-ended cells having uniform rectangular cross sections with edges corresponding to the dimensions of the two largest edges of the packages to be contained therein. The four tubes are then arranged vertically in abutting contact about a central axis to form a four-celled carton in the four quadrants about the axis and having the same overall height and rectangular cross-sectional configuration as the individual cells. The larger external faces of the cells in contact with each other are fastened together, as by rivets or suitable adhesive, and each of the two larger sidewalls of the four-celled carton thus formed, is reinforced by covering with an adhering sheet of material. The individual cells can be made with fold tabs or flaps at one end or both as desired to permit closing of one or both ends of each cell in the same manner as a conventional corrugated paperboard box or shipping container. Such flaps contribute strength and rigidity to the structure. In a preferred embodiment one end of each of the cells does have these end flaps and in assembling the four tubes to form a carton these are placed to form the bottom of the carton.

The bottom of the carton is then capped by a removable tray of paperboard having sidewalls which extend up the outside walls of the carton preferably at least 5 percent of the height but in any event sufficiently to provide close-fitting support for the base of the carton and part of the walls.

The carton is then ready for filling with packages of polymer and in a preferred embodiment each cell of the carton is of a size to receive a seven-bag stack of polymer laid face to face; the face of the bag being the largest flat surface thereof. Natu-

rally it is important that the cross section of the cell be of sufficient size to permit insertion of the bags with reasonable ease but yet small enough to provide a sufficiently snug fit so that the expansion of the bags due to cold flow of polymer is restrained at least to the extent of preventing bursting of the bags.

Experience appears to indicate that a four-celled carton is much more effective in preventing bag bursting due to cold flow than any other configuration. This may be due to support provided at the central axis of the box where all four cells meet. In any event this particular configuration even with a material as weak as corrugated paperboard is effective to prevent bag bursting due to cold flow of polymer.

The invention can be more easily understood by referring to the drawings which show sequential steps for constructing a carton of the present invention. In the drawings FIG. 1 shows a sheet of cardboard 11 creased and folded preparatory to forming the rectangular tube of FIG. 2 having taped joint 15 which bisects one face of the tube, although it can be closer to either side as desired. In this particular embodiment the tube is made with end flaps 12. Four such tubes are made and assembled to produce the four-celled carton shown in FIG. 3, adhesive first being applied to the larger contacting outside faces 13 of the tubes so that these faces will be adhered to each other. Other fastening means can also be used and it is not necessary that the faces be fastened over their entire contacting area. It will be noted that for ease of assembly and carton strength the four tubes are assembled so that the taped joint in each tube is displaced from that in the adjacent tube either by being on opposite sides of a tube, as shown, or by being staggered. Cover sheets 14 are then fastened by convenient means, preferably by adhesive, to opposite faces of the carton to provide support and to hold the cells in place. End flaps 12 are closed as shown in FIG. 4 and the bottom of the carton is capped by tray 17 formed from another sheet of cardboard in conventional manner and having sidewalls 16 which after capping extend partially up the outside walls of the carton. After the cells of the carton are filled with a stack of polymer-loaded packages, the top of the carton is capped with a cover which can be the same as the bottom tray 17. FIG. 5 shows how such a four-celled carton with end flaps can be collapsed for shipping or storage without excessive use of space. FIG. 5 shows the unit partially collapsed and FIG. 6 in a more completely collapsed state. The arrangement of the four cells and the manner of fastening them together permits the carton to be readily collapsed for storage and shipping and, being in one piece except for top and bottom, can be readily set up. The carton can be collapsed completely until its thickness is merely that of the layers of sheet material present. FIG. 7 shows a sheet of cardboard creased and ready for folding to form a top or bottom cover for capping the four-celled carton.

In normal use neither the top nor bottom of the carton need be adhered, riveted, or otherwise fastened to the body of the carton although normally, prior to shipping, the top and bottom are strapped to the box by conventional shipping straps.

Any suitable sheet material can be utilized to make the container of the present invention but corrugated cardboard or paperboard are eminently suitable and probably is the cheapest practical type of material for this use. Any sheet material which can be folded as indicated and has sufficient rigidity to provide the necessary support can be used. Films and fabrics of synthetic and natural sheet materials can be used if desired for all or part of the structure depending upon the particular effect desired. Similarly any suitable adhesive can be used so long as the desired strength is provided. Adhesive is normally applied only to cover sheets 14 and to the external large contacting faces of the conduits during assembly but when greater strength is desired adhesives may also be applied to the smaller contacting faces of the tubes during their assembly if collapse of the structure is not necessary prior to use. Also the top and bottom covers of the carton may be adhered to the body portion to provide greater strength but this has not been found to be necessary for normal usage.

Although adhesives are normally used where indicated above because of convenience, cheapness, and strength, any convenient fastening means can be used including staples, rivets, or interlocking structures built into or added to the walls to be attached.

In order to test a carton of this invention with respect to its effectiveness in preventing bag bursting due to cold flow of ethylene/propylene/1,4-hexadiene terpolymer a carton such as described was constructed entirely of 158 kg. double-wall corrugated paperboard. After folding in the bottom flaps and capping the bottom with a paperboard tray as described, each cell was loaded with 238 kg. of 40 Mooney polymer, the polymer being in polyethylene bags each containing 34 kg. of polymer. Thus there was a stack of seven bags of polymer in each cell. The filled carton was capped with a top cover and a rectangular wood pallet holding four stacks of bagged polymer weighing a total of 1,035 kg. was placed on top of the filled carton. The container was stored in a warehouse at about 23° C. for about 20 days and then shipped a distance of 1,800 miles by truck under the same conditions. It was found that the filled carton and the individual bags of polymer within it were held in practically their original shape by the carton and were in good condition showing very little evidence of deformation. A similar carton tested under the same conditions was 25 equally successful in preventing bag damage.

I claim:

1. A lightweight carton for storing and shipping packaged materials which are subject to settling or flow, said carton comprising
  - a. four rectangular cells assembled in abutting relationship in the quadrants about a central vertical axis to form a four-celled carton having the same rectangular cross-sectional configuration and height as the individual cells,
  - b. one outer face only of each cell being fastened to the abutting outer face of an adjoining cell,
  - c. each of the sidewalls of the carton which are parallel to the fastened cell wall faces, being covered by a sheet material fastened thereto, and

40

- d. the top and bottom of the carton being capped by removable covers which extend partially down the outer walls of the carton.
2. The carton of claim 1 in which the larger contacting outer faces of adjoining cells are fastened together.
3. A four-compartment container assembly comprising four tubular container subassemblies each of rectangular cross section each having two side panels and two end panels with said panels carrying bottom-forming flaps;
  - 10 a first two of said container subassemblies being joined together in transverse aligned relation at a single side panel to form a first pair of joined container subassemblies;
  - 15 a second two of said container subassemblies also being joined together in transverse aligned relation at a single side panel to form a second pair of joined container subassemblies;
  - 20 said first and second pairs being arranged to form an array in which end panels of the subassemblies of one pair are in adjacent opposed relation to end panels of the subassemblies of the other pair with the subassemblies of one pair in longitudinal alignment with the subassemblies of the other pair;
  - 25 a rigid reinforcing panel secured on each of the two opposite sides of the array to the outer faces of the aligned subassembly side panels;
  - 30 the two remote subassembly end panels of the array being exposed and forming the end faces of the container assembly,
  - 35 the adjacent and facing end panels of the container subassemblies being unattached and capable of being separated to form a diamond-shaped configuration and the opposite exposed subassembly end panels forming an angular configuration with the apices of the configuration extending outwardly from the center of the assembly as said reinforcing panels are moved toward each other to collapse said four-compartment container and provide a substantially flat contour for the collapsed container.
